DESIGN.

F. MANKEY.

OPEN WORK PANEL.

No. 16,460.

Patented Jan. 12, 1886.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 16,460, dated January 12, 1886.

Application filed November 13, 1885. Serial No. 182,767. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

Extending through the panel are rectangular openings A, appearing in rows at regular intervals. Upon the face of the panel and between said openings appear rectangular elevations B C, having beveled outer edges, as D. The elevations C are smaller than and alternate with the elevations B in rows both

laterally and transversely the panel. Between said elevations are grooves or channels E. Around each opening A is a narrow surface, F, flat and on the same level as the bottoms of channels E.

20

I claim—

The design for an open-work panel, substantially as herein shown and described, which consists of the rectangular openings A, and on the face of the panel the rectangular elevations B C, with intermediate channels, E. 25

FREDERICK MANKEY.
